UNITED STATES PATENT OFFICE.

JOHN G. GOMILA, OF NEW ORLEANS, LOUISIANA, ASSIGNOR TO WORLD BOTTLING CO., LTD., OF NEW ORLEANS, LOUISIANA.

DESIGN FOR A BOTTLE.

Application filed November 14, 1925. Serial No. 15,421. Term of patent 14 years.

To all whom it may concern:

Be it known that I, JOHN G. GOMILA, a citizen of the United States, residing at New Orleans, Louisiana, in the parish of Orleans, have invented a new, original, and ornamental Design for Bottles, of which the following is a specification, reference being had to the accompanying drawing, forming a part thereof.

The figure is a side view in elevation of a bottle, showing my new design.

I claim:

The ornamental design for a bottle, as shown.

JOHN G. GOMILA.
